Primary Examiner — Sheryl Lane*Assistant Examiner* — Mark T. Philipp(74) *Attorney, Agent, or Firm* — Nelson Mullis Riley & Scarborough LLP(57) **CLAIM**

The ornamental design for a fuel dispenser housing, substantially as shown and described.

DESCRIPTION

FIG. 1 is a perspective view of a new, original, and ornamental design of a fuel dispenser housing in accordance with the present invention;

FIG. 2 is a front side elevation view thereof;

FIG. 3 is a right side elevation view thereof, with the left side elevation view being identical thereto;

FIG. 4 is a top side plan view thereof;

FIG. 5 is a bottom plan view taken along the line 5-5 of FIG. 3; and,

FIG. 6 is a bottom side plan view thereof.

The broken lines represent portions of the article, and form no part of the claimed design.

1 Claim, 6 Drawing Sheets(56)
